UNITED STATES PATENT OFFICE.

HARRY THOMSON, OF HOUSTON, TEXAS, ASSIGNOR TO STANCLIFFE WELL SCREEN & MANUFACTURING COMPANY, OF HOUSTON, TEXAS, A CORPORATION OF TEXAS.

SCREW-TYPE WELL PACKER.

Application filed June 29, 1925. Serial No. 40,425.

My invention relates to well packers and pertains particularly to canvas packers adapted to be compressed longitudinally and thus expanded laterally to close the space 5 within the well casing at the upper end of the well strainer.

It is an object of the invention to provide a packer which will expand uniformly and serve to tightly fill the space to be packed off 10 thereby. It is a further object that the device be adapted to be again contracted, after expansion, so that it may be withdrawn from or relocated in the well when desired. The device is further adapted to be inserted or 15 withdrawn from the well without the use of a special setting tool.

Further objects of the invention will appear from the specification which follows. In the drawing, a preferred form of the invention is disclosed. Figs. 1 and 2 are longitudinal views partly in central section of the invention, Fig. 1 illustrating the upper end and Fig. 2 the lower end of the assembled device. Fig. 3 is a transverse section on the plane 3—3 of Fig. 1. Fig. 4 is a side elevation of my packer placed in the casing. Fig. 5 is a similar elevation showing the packer in "expanded" position. Fig. 6 is a transverse section on the plane 6—6 of Fig. 2, the canvas 25 strips being shown somewhat diagrammatically. Like numerals of reference designate like parts in all the views.

My packer is particularly adapted to close the space around the upper end of the strainer within the lower end of the casing; it is employed most commonly in finishing the well to determine whether the same is a producing well or not. It is desirable that the packer be capable of being placed and 35 set to test the well, but if the test is found to be unsuccessful, it is desirable that the packer be capable of being withdrawn, for further development of the well. The packer is adapted to close the space between the casing 40 and the strainer, or about a well tubing, if so desired.

In carrying out the invention, I secure at the upper end of the strainer 1 a tubular mandrel 2, said mandrel being secured to the 45 strainer by means of a coupling or collar 3.

The mandrel is threaded with a coarse thread 4 along the upper half thereof to provide engagement for a nipple 5.

The said nipple 5 comprises a pipe or collar, the ends of which are thickened inwardly 55 and threaded to be screwed down over the mandrel allowing the mandrel to project upwardly therein. At the upper end of the nipple a short connecting pipe 6 is secured and it is contemplated that the threaded connection will be formed by a so-called left-hand thread, that is, one whereby the connection is made between the section 6 and the nipple by screwing downwardly with a counter clockwise turn of the pipe section. 60 This connection makes it possible to disengage the connecting pipe 6 from the nipple by a right-hand or clock-wise rotation of the drill stem to which the packer may be secured. The connection between the section 70 6 and the nipple may be reinforced, if desired, by a pin 7 of frangible material which is extended radially through the upper end of the nipple and the connecting pipe. 65

The lower end of the nipple 5 is undercut 75 to provide an overhanging skirt 8 spaced away from the outer threaded face of the mandrel. An inner groove 9 is formed in said skirt to accommodate a series of balls 10 forming a roller bearing between the said 80 skirt and the upper reduced portion 11 of a slip 12. Said slip is also grooved to register with the groove in said skirt, thus forming a ball race in which the balls may roll. This arrangement provides a swiveled connection 85 between the slip 12 and the nipple; it permits the rotation of the nipple upon the slip, allowing the slip to remain non-rotatable upon the mandrel while the nipple is being screwed downwardly.

The slip 12 fits loosely over the threaded end of the mandrel and is tapered downwardly at 13 for a suitable distance to assist in the expansion in the packer, as will be presently described.

The slip has secured at its upper end adjacent the swiveled connection a packer comprising a series of longitudinal strips of flexible material 14 which will, under ordinary circumstances, be canvas or the like, but may 100

be of any flexible and compressible material. The strips are secured in overlapping arrangement, as shown in Fig. 6. The upper ends are engaged within an undercut groove 15 formed by the upper end of the slip, the canvas strips being retained therein by rolling or otherwise forcing the outer wall of the groove inwardly against the packing to clamp it securely in position. This forms a secure hold upon the packing material and interferes in no way with the operation of the device.

The lower ends of the packing strips 14 are secured within a groove 16 formed by undercutting the upper end of the collar 3 so that it will overlap the lower ends of the said packing strips; it is then bent inwardly to clamp the packing strips in position. An intermediate band, or hoop 17, may be secured about the packing strips at a point adjacent the lower end of the slip 13, if desired, and such band is shown in the drawing. This band assists in holding the strips in contracted position while the device is moved 25 to or from its position at the bottom of the well.

In assembling the device, the strips 14, constituting the packer, are secured to the slip 13 as described. The slip is then secured upon the lower end of the nipple 8. This is done by fixing the slip in the lower end of the nipple and then placing the balls in position within the groove 9. This is done by providing an opening 18 in the outer wall of the skirt 8 and inserting the balls through said opening one by one until the groove is entirely filled. The opening may then be stopped by a threaded plug, or by solder, if desired. The mandrel is then screwed with- 40 in the lower end of the nipple and the packing strips secured at their lower end within the collar 3.

When the device is inserted into the well, the strainer 1, and perhaps a pipe section 45 thereon, are secured at the lower end of the coupling 3, and the device is lowered downwardly within the casing 19. When the lower end of the strainer engages the bottom of the well, the packer may then be expanded by compressing it longitudinally, thus forcing it outwardly against the casing. In Fig. 4 the packer is shown in extended or unexpanded position. The rotation of the 50 drill stem, which is employed to operate the device, will cause the rotation of the nipple 5 screwing it downwardly over the mandrel which remains stationary in the well. The slip 13 serves to assist in maintaining the packer against rotation with the nipple, the 55 swivel engagement allowing the stationary position of the packer. As the nipple 5 is moved downwardly on the mandrel, the packer will be compressed longitudinally, and in Fig. 5 the packer is shown partially ex- 60 panded, and it will be noted that the strips 65

are compressed uniformly downward without twisting upon the mandrel. The lower portion of the packing strips will be expanded first, due to the presence of the slip 13 which moves downwardly with the upper end 70 of the packing strips so as to first expand the lower end; this avoids the engagement of the upper end of the packer first with the casing which would prevent complete expansion of the lower end thereof. The slip also serves 75 to assist in forcing the packing strips outwardly against the casing. When fully expanded, the packing strips will form a uniformly tight closure between the mandrel and the well casing in an obvious manner.

When the packer is fully set, the resistance to further downward screwing of the nipple upon the mandrel will become so great that the connecting pipe section 6 will begin to exert a strain upon the threaded connection between the same and the nipple breaking the pin 7 and rotating the pipe connection to unscrew it from the packer. The drill stem and the pipe section may then be withdrawn, if desired.

If it becomes desirable to remove or change the packer, the drill stem may be again inserted downwardly and rotated in a left-hand direction to engage the section 6 with the upper end of the nipple. The rotation thereafter with the nipple in the opposite direction will screw it upwardly along the mandrel contracting the packing material and releasing the packer from the casing so that it may be withdrawn. A radial pin 20 is provided between the threads at the upper end of the mandrel to limit the upward screwing of the nipple upon the mandrel, and thus serves to indicate to the operator when the packer has been fully extended and ready for withdrawing; the packer may then be withdrawn without difficulty.

The advantages of this construction lie in the fact that the packer is arranged to be compressed by a straight longitudinal movement of the slip upon the mandrel so that it will be compressed uniformly without twisting. This avoids the uneven expansion which is sometimes obtained by spirally arranged packing material which is liable to stick to the mandrel at some points before the device is fully expanded. The use of the slip also serves to assist in expanding the packer uniformly from the lower end upwardly until the whole packer has been uniformly expanded. The swivel engagement between the slip and the nipple is peculiarly efficient for this purpose and forms an important part of the invention. The further objects and advantages of the device will be obvious to those skilled in the art without further description.

What I claim as new and desire to protect by Letters Patent is:

In a packer for wells, a tubular mandrel, a

collar connecting with said mandrel, said mandrel being coarsely threaded at its upper end, a nipple having threaded engagement with the upper end of said mandrel, a downwardly tapered slip suspended on and having rotative engagement with the lower end of said nipple outside said mandrel, a canvas

packer on said slip and mandrel and secured at its lower end to said collar, and means to connect said nipple to a tubular drill stem. 10

In testimony whereof I hereunto affix my signature.

HARRY THOMSON.
